PROCESS FOR OBTAINING CONTRASTS BY
MEANS OF DIAZONIUM COMPOUNDSJan Hendrik De Boer, Cornelis Johannes Dippel,
and Roelof Jan Hendrik Alink, Eindhoven,
Netherlands, assignors to N. V. Philips' Gloei-
lampenfabrieken, Eindhoven, NetherlandsNo Drawing. Application May 19, 1932, Serial
No. 612,364. In the Netherlands May 22, 1931

5 Claims. (Cl. 95—6)

This invention relates to a method of obtaining photographic contrasts by means of diazonium compounds. The so-called diazo type is known to be based on the production of azo dyes by the coupling of a diazonium compound with an azo component and in addition to the fact that diazonium compounds are decomposed by exposure and are thus deprived of their property of coupling with azo-components to form azo-dyes. Thus, for example, methods are known according to which paper provided with diazonium compounds is exposed under a diapositive or a drawing and then treated with a solution of an azo-component. The non-exposed parts are thus coloured so that a positive of a positive is obtained. A further known method involves the use of paper containing a diazonium compound which on exposure is converted into a phenol which is then used as an azo component. In this case the phenols thus obtained may be caused to couple with some diazonium compound, but it is also possible to bring about a coupling with the diazonium compound from which the said phenol is produced. For this latter purpose it is often necessary to introduce the paper into an alkaline medium. If indeed an exposure through a negative is made so that at the exposed spots a sufficient quantity of diazonium compound has remained, it is possible to cause the phenol formed to couple with the diazonium compound still present by introducing the aggregate into an alkaline medium.

The method according to the invention is based on quite a different principle: it does not utilize the coupling properties of diazonium compounds but is based on the oxidizing properties of certain diazonium compounds.

The properties in question of diazonium compounds will be set out more fully by reference to an example. If, for example, p-hydroxybenzenediazoniumchloride is exposed (as is well known there is in the usual carriers, such as paper, always sufficient water to give rise to the occurrence of an OH-group) there is formed therefrom hydroquinone, nitrogen and hydrochloric acid according to the equation:

If the exposure is made so that only part of the diazonium compound present is converted into hydroquinone, the hydroquinone is oxidized by the diazonium compound to form a coloured oxidation product. As stated above, it is on this principle that the invention is based.

55 The method of producing contrasts by means of

light according to the invention consists in the use of a carrier provided with a diazonium compound (or with a plurality of such diazonium compounds) which on exposure in the presence of water forms primarily a phenol so substituted in the benzene nucleus that this phenol can be oxidized by the diazonium compound itself or by a further diazonium compound also present in the carrier to form a colored compound, the medium of the carrier being such that the speed at which this oxidation process proceeds is greater than that at which the diazonium compound couples with the phenol to form an azo-dye but during the exposure is smaller than that at which the diazonium compound is converted by the said exposure, and that the phenol is caused to be oxidized by the diazonium compound not yet converted to form a colored oxidation product.

The invention includes also a method of obtaining heliographic prints which is characterized by the use of a carrier provided with a diazonium compound which, after the local exposure and without any other substance being added after the exposure, is caused to form a dye which is not an azo-dye.

As examples of diazonium compounds suitable for use in carrying out the present invention we may mention those having in the benzene nucleus at least one OH-group substituted in ortho or para position relatively to the diazonium group. In some cases the OH-group, which in the benzene nucleus is substituted in ortho or para position relatively to the diazonium group, may be replaced by a NH₂ group one of the hydrogen atoms of which may be replaced in some cases by an alkyl-, aryl-, or similar group.

According to one embodiment of the invention diazonium compounds are used which after the exposure yield polyphenols which are not adapted in any way to couple with diazonium compounds.

The invention will now be set out more fully with reference to various embodiments.

Example 1

Paper provided with p-hydroxybenzenediazoniumchloride is first exposed beneath a drawing to that part of the spectrum which is particularly actinic relative to the compound mentioned in this example, the drawing being preferably applied to material that is readily transparent to the light of the desired wave-band. The wave length that is particularly actinic relatively to the compound mentioned in the example is in the neighbourhood of 3000 Å. The parts struck by this light first

- exhibit an intermediate red violet colour which on continued exposure changes to light yellow. It may be observed in this connection that this whitening of the intermediate red violet colour 5 also ensues when the exposed paper is kept in daylight or even in the dark. After the said strongly actinic exposure the paper, with the drawing removed, is exposed to daylight. Daylight is much less actinic relative to the diazonium compound 10 mentioned in this example so that there is now a question of a slightly actinic exposure. Even during this exposure the hydroquinone formed in consequence thereof is oxidized by the diazonium compound not yet converted to form a brown 15 coloured oxidation product so that a positive of a positive is produced. The paper above described contains a diazonium compound which on exposure yields a polyphenol that is not adapted to couple with a diazonium compound to form an 20 azo-dye, since hydroquinone is not possessed of this property. As an alternative, the slightly actinic exposure may be obtained by short exposure to light having a high specific actinic effect 25 relatively to the diazonium compound used or to a feeble light source producing such light. Alternatively, the action may be influenced by altering the distance of the light source.

Example 2

- 30 Paper is provided with orthohydroxybenzenediazonium chloride; otherwise, the process may be carried out similarly to Example 1. The diazonium compound used in this case differs from that mentioned in the first example in that the 35 intermediate colour produced by the strongly actinic exposure is orange red.

According to one embodiment of the invention the stability of the paper provided with a diazonium compound but not yet exposed may be increased by choosing as the acid residue of the diazonium compound a slightly volatile acid, such as sulphuric acid; for this purpose, preferably, a diazonium compound may be used which contains a sulpho acid group substituted in the nucleus.

45

Example 3

- Paper is provided with 1-hydroxy-2-diazo-4-benzenesulphonic-acid. The strongly actinic exposure under a drawing is now effected by daylight, because daylight is strongly actinic with respect to the said compound; on the contrary for the slight actinic exposure ultraviolet light may be resorted to because ultra-violet light is slightly actinic with respect to the said diazonium 50 compound. Otherwise, the process may be effected similarly to the above examples so that consequently also a positive of a positive is obtained. The coloured oxidation product has an orange red colour whereas the base is light yellow. In 55 connection with the examples described the remark applies that the slightly actinic effect may be obtained by a very short exposure to the light source used for the strongly actinic exposure and then the oxidation of the phenol formed may be brought about by the diazonium compound by 60 subsequent preservation in the dark.

In connection with the examples described it may be observed that paper normally contains sufficient water for the conversion of the diazonium compound into the phenol by the exposure.

According to a particular embodiment of the invention, the oxidation reaction can be considerably accelerated by a moderate heating, for 75 instance to 80° C. In view of this acceleration of

the oxidation reaction it is preferable that during the strongly actinic exposure the paper should be kept as cold as possible as otherwise the base is coloured too much.

Often, for obtaining a slightly actinic exposure, 5 it is not necessary to expose on purpose as even during the manipulation such exposure is obtained spontaneously whereupon the heating may be effected.

According to a further embodiment of the invention, 10 the formation of contrasts can be considerably promoted by means of copper salts, such as copper nitrate.

Example 4

15

Paper is soaked in a 0.25% alcoholic solution of 1-hydroxy-2-diazo-4-benzenesulphonic acid having added to it 0.55% of copper nitrate. After drying it is exposed under a drawing for 20 seconds to a carbon arc lamp (for example in a 20 heliographic printing machine), after which the drawing is removed and the paper is heated for some time to 80° C. Thus a positive of a positive in a dark grey tone is obtained.

The invention is based on the oxidation of the 25 product produced from the diazonium compound by exposure so that for use in carrying out the invention such diazonium compounds are particularly suitable which yield on exposure readily oxidizable products which are oxidized by the 30 diazonium compound to form a dark-coloured oxidation product. The invention presents inter alia the advantage that the particularly suitable diazonium compounds just referred to are simple compounds having their diazonium group in a 35 benzene nucleus. Very good contrasts may be obtained with those diazonium compounds that have an OH-group in the ortho or para position in the benzene nucleus. Alternatively, use may be made of a multiple diazotized polyamino compound which on exposure passes into a polyphenol, in which case the compound should be such that two of the diazonium groups are in ortho or para relation to each other.

As is apparent from the foregoing, the present 45 invention permits of producing so-called integral heliographic prints which obviate the need for some chemical after-treatment. A chemical after-treatment is even preferably avoided in some cases, particularly an after-treatment with 50 alkali, such as gaseous aqua-ammonia, since in a medium of aqueous-ammonia an oxidation, by oxygen from the air, of the compounds at the spots copied out by the strongly actinic exposure ensues as well. In order to avoid this difficulty, 55 which also occurs in the case of well-known heliographic print-papers during the aqueous-ammonia treatment necessary in such case for bringing about the coupling to form azo-dyes, it has been proposed to add beforehand to the 60 paper reducing compounds preventing the so-called yellowing. It is, of course, obvious that as in the case of the papers according to the invention no aqua-ammonia treatment needs to be carried out, the said reducing substances are 65 redundant. The addition of some of such reducing substances even defeats the oxidation by the diazonium compound still present as aimed at by the invention. In addition, an aqueous ammonia-treatment is not very desirable in those 70 cases in which there is still a slight likelihood of coupling, as the azo-dyes produced by coupling are generally less durable than the dyes obtained by oxidation according to the invention. Since the well-known heliographic print papers are 75

based on the formation of azo-dyes and those according to the invention on dyes produced by oxidation, prints according to the invention have a greater durability, which constitutes an advance in this field.

Although with those compounds which by exposure are converted into a polyphenol that cannot serve as an azo component such as hydroquinone, the oxidation reaction can be accelerated by an aqueous ammonia-treatment, this treatment has the disadvantage mentioned before that consequently the white portions subjected to the strongly actinic exposure may be oxidized by oxygen from the air so that they become darker in tone.

As mentioned above some diazonium compounds having at least one NH_2 group in ortho or para relation to the diazonium group in the benzene nucleus are also suitable for use in carrying out the invention. On exposure said diazonium compounds pass into an amino phenol which by the diazonium compound from which it is formed can be readily oxidized to form a coloured oxidation product. We quote below an example of the use of such a diazonium compound.

Example 5

Paper treated with a solution of p-phenyl-
30 aminobenzenediazonium chloride,

is exposed under a drawing on transparent paper to violet light which in this case is strongly actinic, after which it is heated out of contact with the drawing to 80°C .

In all of the examples above described it is advantageous to provide the paper unilaterally with the light sensitive substance. Thus not only 40 a saving in material is obtained but the reverse of the paper which naturally is only slightly exposed is prevented from becoming dark coloured by the oxidation reaction occurring in that case.

When an alcoholic solution of the light sensitive substance is used for the manufacture of the heliographic print paper, the reverse side of the paper becomes light sensitive, because such a solution penetrates very quickly through the paper. The darkening of the reverse side 50 of such paper can be avoided in that during or subsequent to the exposure also this side of the heliographic print material is strongly exposed and preferably to such extent that it is copied out as completely as possible. Heliographic print paper treated in this manner can therefore not receive a dark colour on its reverse side during the development of the image as a result of the copying out, as all of the diazonium compounds present thereon is converted by the light.

According to another embodiment of the invention, instead of paper other materials, such as glass, film or paper provided with a gelatine layer, may be used as the carrier of the diazonium compounds described. Such material permits of 60 obtaining photographic prints by carrying out the invention which will be set out more fully by reference to some examples.

Example 6

70 A paper carrier coated with gelatine is introduced into a 1% solution of ortho-phenol diazonium sulphate in water having added to it about $\frac{1}{2}\%$ of copper sulphate. After drying it is exposed to sunlight under a photographic negative, preferably for one or two minutes if the

carrier material of the photographic negative is glass. It is then rinsed out with water and thus a print in a sepia shade is obtained. The exposure applied in this example is slightly actinic relatively to the diazonium compound here 5 mentioned so that at the spots upon which light has fallen, part of the diazonium compound is converted into a polyphenol; the greater the quantity of light falling on those spots the greater being the quantity of the diazonium compound 10 converted. During the said rinsing with water, the polyphenol formed is oxidized by the excess of the diazonium compound present to form a coloured oxidation product and the greater the quantity of light that has acted the darker are 15 the tones obtained, as the coloured oxidation product is insoluble. The excess of diazonium compound is washed out.

Preferably, the exposure is so effected that even at those spots upon which most of the light 20 has fallen there remains always an excess of diazonium compound. On the contrary, an unduly prolonged exposure results in copying out and thus less dye formation or no dye formation at all can be obtained so that in the case of an 25 excessively long exposure even a negative of a negative is obtained. If, when using the diazonium compound mentioned in the Example 6, it is desired to expose to ultra-violet light, preferably a much shorter exposure time is chosen. 30

Example 7

If, instead of the diazonium compound mentioned in example 6, 1-hydroxy-2-diazo-4-benzenesulphonic acid is used—a diazonium compound relatively to which sunlight is strongly actinic—the exposure time for obtaining photographic prints must be shorter. When a negative on glass is used, an exposure to sunlight of from 40 $\frac{1}{4}$ to $\frac{1}{2}$ min. is more than sufficient.

In contradistinction to examples 6 and 7 in which paper provided with gelatine is used as the carrier of the diazonium compounds, we shall give below an example in which a sheet of regenerated cellulose is chosen as the carrier for 45 the diazonium compound.

Example 8

A sheet of regenerated cellulose known under the registered trade-mark "cellophane" is soaked 50 in a $\frac{1}{2}\%$ aqueous solution of 1-hydroxy-2-diazo-4-benzenesulphonic acid containing 1% of copper nitrate. After drying it is exposed under a photographic negative for about $\frac{1}{2}$ min. to glaring 55 diffused daylight; after that it is washed out with water so that a positive print having a blue hue is obtained which is quite satisfactory, particularly in transmitted light.

In the case of photographic uses in which regenerated cellulose serves as the carrier of the diazonium compound, or glass, film or paper or the like provided with a gelatine coating to which the Examples 6, 7 and 8 refer, it may be preferable that the oxidation reaction should be accelerated by bathing for a short time in aqua-ammonia. As in the case of these photographic uses 60 preferably water is used for washing out and the aqua-ammonia treatment is only of short duration, neither oxidation of the bottom by oxygen from the air nor coupling practically ensues 65 in this case.

According to a particular embodiment of this photographic use the carrier may be treated, prior to its being washed out with water, with an ammoniacal copper solution which obviates the need 75

of adding copper salt to the diazonium compound of the carrier.

Even when paper not provided with a gelatine layer is used as the carrier, the washing operation with water described hereinbefore may be resorted to. If, however, in this case the washing operation is effected immediately after the exposure, generally vague melting images are obtained by reason of the diazonium compound being washed out too quickly relatively to the speed at which the oxidation occurs. If, therefore, it is desired to carry out the washing-out operation in the case of paper, it is preferable that after the exposure the paper should be kept for some time in the dark before it is washed out with water so as to allow time for oxidation during this preservation and consequently for the formation of dyes.

Generally, it may be observed that the durability of soaked papers is greater than that of soaked gelatine papers and "Cellophane".

For the examples it will be seen that the diazonium-compounds adapted for carrying out the invention do not group themselves according to the usual system of organic chemistry.

The invention may also be practised for making direct photographic exposures, in which case generally longer exposure times are used, since usually the quality of actinically active light available is smaller.

In connection with the nature of the light sensitive material referred to hereinbefore it may be advantageous, in order to obtain better contrasts, to give the carrier during the heating operation the desired degree of humidity. For this purpose it is preferable to provide the heliographic printing device with humidifying means.

According to a further embodiment of the invention it is possible to also expose the reverse 40 of the paper so that copying out ensues there which assists in obtaining a light reverse of the paper. This may be advantageous when on being applied light sensitive substance has reached the reverse of the paper, which occurs for example if 45 the paper is treated with an alcoholic solution of the light sensitive substance.

It is possible to cause the exposure and the development of the light sensitive material to be brought about each in a separate device.

As has been stated, the diazonium compounds adapted for carrying out the invention do not group themselves according to the usual system of organic chemistry. However, the light-sensitive substances used are broadly light-sensitive benzene-diazonium compounds; of these a great number and variety are adapted to carry out the invention. Especially good results are obtained with p-hydroxy-benzene-diazonium-chloride; ortho - hydroxy - benzene - diazonium chloride; 1-hydroxy-2-diazo-4-benzene sulfonic acid; p-phenolamino - benzene - diazonium chloride; ortho-phenol diazonium sulphate; and in general with such benzene-diazonium compounds in which the benzene nucleus comprises at least one OH group substituted in ortho or para position with regard to the diazonium group, or in which an NH₂ group is similarly substituted in the benzene nucleus, or in which one of the hydrogen atoms of this NH₂ group is replaced by an alkyl-, aryl, or similar group. Such light-sensitive benzene-diazonium compounds, under proper conditions, if subjected to suitable selective actinic exposure, will decompose at exposed portions to form a decomposition product (phenol), which, with the undecomposed diazonium compound of its sur-

roundings, will enter into a reaction, i. e., be oxidized by the same and form a colored oxidation product, provided, due to proper selection of the milieu of the layer, the speed of oxidation is less than the speed of decomposition (conversion) of the diazonium compound during the exposure, and provided the speed of oxidation is greater than the speed at which the decomposition product (phenol) produces, with the diazonium compound, an azo-dye. This formation of colored matter takes place to a great extent subsequent to the actual exposure, and as a rule without further exposure or addition of any further substance after the exposure, and thus a "self-development" of the light-sensitive layer takes place.

In the claims the term "selectively exposing" should refer to the exposing of the carrier provided with a light sensitive diazonium compound, both through a suitable negative or positive.

What we claim is:

1. The process of making light prints comprising the steps, forming a light sensitive layer by applying to a carrier a light sensitive substance comprising a benzene-diazonium compound, selectively exposing said carrier to actinic light to partially decompose the diazonium compound at selected portions, forming a phenol and oxidizing into colored products the phenol so formed by the undecomposed diazonium compound remaining at these portions, by providing a speed of oxidation which is greater than the speed at which the benzene-diazonium compound would form an azo dye with the phenol, said selected portions forming a colored contrast with the substantially uncolored remainder of the carrier.

2. The process of making light prints comprising the steps, forming a light sensitive layer by applying to a carrier a light sensitive substance comprising a benzene-diazonium compound, selectively illuminating said layer with a strongly actinic light to partially decompose on selected portions said diazonium compound, forming a phenol substituted in the benzene nucleus and oxidizing said phenol by non-decomposed diazonium compound at the weakly-illuminated portions at a rate which is greater than the rate at which the diazonium compound could couple with the phenol to form an azo dye, to thereby form on said weakly-illuminated portions a colored oxidation product, and photochemically decomposing during said illumination the diazonium compound at the strongly-illuminated portions at a rate which is greater than is the rate of oxidation of the phenol, to maintain said strongly illuminated portions substantially uncolored.

3. Process of making light prints comprising the steps, forming a light sensitive layer by applying to a carrier a light sensitive substance comprising a benzene-diazonium compound, selectively illuminating said layer with weakly actinic light to partially decompose on said selected portions said diazonium compound forming a phenol substituted in the benzene nucleus, and oxidizing said phenol by a non-decomposed diazonium compound at a rate which is greater than the rate at which the diazonium compound could couple with the phenol to form an azo dye, to thereby form on said portion a colored oxidation product, and thereafter subjecting the undecomposed benzene-diazonium compound remaining in the carrier to treatment to prevent color formation on the non-selected portions of the carrier.

4. The process of making light prints comprising the steps, forming a light sensitive layer by applying to a carrier a light sensitive substance

comprising a benzene-diazonium compound, selectively exposing said carrier to actinic light to partially decompose the diazonium compound at selected portions, forming a phenol in the presence of water and oxidizing into colored products the phenol so formed by the undecomposed diazonium compound remaining at these portions, by providing a speed of oxidation which is greater than the speed at which the benzene-diazonium compound would form an azo dye with the phenol, said selected portions forming a colored contrast with the substantially uncolored remainder of the carrier.

5. The method of producing a photographic print comprising the steps of providing on a carrier a light sensitive benzene-diazonium compound selected from the group p-hydroxybenzenediazoniumchloride, 1-hydroxy-2-diazo-4-ben-

zene-sulphonic-acid, orthohydrobenzenediazoniumchloride, p-phenylaminobenzenediazoniumchloride, orthophenoldiazoniumsulphate, selectively exposing said carrier to actinic light to partially decompose the diazonium compound at selected portions, forming a phenol and oxidizing into colored products the phenol so formed by the undecomposed diazonium compound remaining at these portions, by providing a speed of oxidation which is greater than the speed at which the benzene-diazonium compound would form an azo dye with the phenol, said selected portions forming a colored contrast with the substantially uncolored remainder of the carrier.
